(57) **CLAIM**

The ornamental design for a toy belt, as shown and described.

DESCRIPTION

FIG. 1 is an exterior view of the toy belt;

FIG. 2 is an interior view of the toy belt;

FIG. 3 is a bottom view of the toy belt;

FIG. 4 is a top view of the toy belt;

FIG. 5 is a buckle end view of the toy belt;

FIG. 6 is an insertion tab end view of the toy belt; and,

FIG. 7 is a perspective view of the toy belt, donned by a wearer and with a plurality of toy straps attached to the toy belt and toys attached to the toy straps.

FIG. 7 illustrates a plurality of toy straps attached to the toy belt and toys attached to the toy straps, respectively, with the toy belt donned by a wearer, which wearer, toy straps and toys are illustrated in broken lines and form no part of the claimed design.
